AMINE SALTS OF 8-HALOTHEOPHYLLINE

James M. Holbert, Lookout Mountain, and Irvine W. Grote, Chattanooga, Tenn., assignors to The Chattanooga Medicine Company, Chattanooga, Tenn., a corporation of Tennessee

No Drawing. Application August 8, 1951,
Serial No. 240,988

5 Claims. (Cl. 260—253)

The present invention relates to a pharmaceutical compound having enhanced diuretic activity, and comprises a halotheophylline salt of organic amines having at least one primary amino group in the molecule.

We are aware that theophylline itself has previously been combined with various amines for the purpose of solubilizing the theophylline in diuretic compositions. Probably the most common derivative of this type is theophylline-ethylene diamine, known under the common name "aminophylline."

We have now found that if the theophylline of this type of composition is replaced by a halotheophylline, particularly 8-bromotheophylline, and 8-chlorotheophylline, not only is the solubility of the theophylline composition increased to a greater degree than occurs from the reaction between theophylline and the same amine compounds, but the resulting salt is far superior as a diuretic compound to the previously known diuretic compounds containing theophylline.

The remarkably increased diuretic properties of the halotheophylline-amine salts of the present invention make them valuable therapeutic agents in the relief of premenstrual tension, a condition upon which previously known derivatives of theophylline had little or no effect.

A large percentage of women, estimated at 30 to 60%, suffer from pre-menstrual tension in varying degrees during the menstrual age. These women accumulate water in the body tissues during the week preceding the menses in varying amounts, the amount usually varying from 1 to 5 pounds. The symptoms of such water accumulation are headache, breast fullness and soreness, abdominal distension, low back pain, extreme nervousness, swelling of the ankles, increased appetite, irritability, pelvic pain, and a feeling of tension. The severity of the discomfort is directly commensurate with the amount of fluid accumulated or pounds of weight gained. Women who gain from 3½ to 4 pounds during the week preceding the menses are almost incapacitated due to the severity of the symptoms from water toxemia.

The compounds of the present invention are singularly efficient in the relief of the symptoms associated with pre-menstrual tension. Patients to whom the compositions of the present invention are administered approximately one week before the onset of menses rarely gain more than one and one-half pounds, and in many cases no weight gain whatsoever is observed. Furthermore, patients who are placed under treatment with the products of the present invention, even after they have gained weight, have a diuresis within a few hours after beginning treatment, resulting in the prompt relief of the symptoms.

One outstanding characteristic of therapeutic products of the present invention in the treatment of pre-menstrual tension is that in most patients they prevent water accumulation without diuresis if the treatment is started early enough so that the patients have no symptoms of water toxemia throughout their pre-menstrual period.

2

An object of the present invention is to provide a therapeutic product comprising a halotheophylline salt of an organic amine for use in the relief of pre-menstrual tension without the presence of side reactions usually associated with the administration of theophylline.

Another object of the present invention is to provide a compound capable of effecting unlocking pitressin-induced edema in human females.

Another object of the present invention is to provide a theophylline derivative having a high water solubility and a high degree of diuretic activity.

Still another object of the present invention is to provide a diuretic composition of enhanced activity which is capable not only of releasing added water but previously retained water from human body tissues.

The compositions of the present invention are prepared by reacting an 8-halotheophylline, such as 8-bromotheophylline or 8-chlorotheophylline, with an organic amine compound characterized by the presence of a primary amino group (NH₂) on a hydrocarbon chain of not more than 6 carbon atoms. The simplest compounds within the scope of the present invention are the halotheophylline derivatives of relatively short chain primary alkyl amines such as methylamine, ethylamine and n-butylamine. Other amine compounds whose halotheophylline derivatives are within the scope of the invention are the unsaturated aliphatic monoamines such as allylamine. Furthermore, the primary amino group in the molecule need not be attached to a straight chain hydrocarbon group as long as the group is aliphatic. Thus, suitable derivatives are made for the purpose of the present invention by reacting cyclohexylamine with the halotheophylline.

Other amine compounds which form suitable halotheophylline derivatives are the alkanol amines such as monoethanolamine, 2-amino-2-methyl-1-propanol, 2-amino-2-methyl-1,3-propanediol, and tri-(hydroxymethyl) amino methane.

Other amino compounds that can be used for the purposes of the present invention are the alkylene diamines such as ethylene diamine, propylene diamine, and hexamethylene diamine. In addition, the lower poly-alkylene polyamines, such as diethylenetriamine and triethylenetetramine, can also be employed. Certain aralkyl amines are also within the scope of the present invention. These are the amines in which a primary amino group appears in a hydrocarbon chain attached to an aryl nucleus, with only one aryl nucleus in the molecule. Compounds such as benzylamine and p-methoxy-benzylamine are typical of this type of compound. These aryl alkyl amines should be differentiated from strictly aromatic amines such as aniline and homologues of aniline in which the amino group is attached directly to the benzene ring. The strictly aromatic amines are not particularly suited for the purposes of this invention.

The method to be used for the preparation of the salts of the amines with the halotheophylline depends primarily upon the solubility characteristics of the amine compound used. If the amine is soluble in water, the theophylline derivative is dissolved in an aqueous solution containing an excess of the amine. If necessary, the solution may be gently warmed to effect complete dissolution. The resulting solution is then filtered and evaporated at reduced temperatures and pressures until the salt combination begins to crystallize. The solution is then cooled to promote separation of the salt and the resulting crystals are removed by filtration, after which the material is dried in a vacuum desiccator.

Alternately, the halotheophylline, ground to a fine powder, may be mixed directly with a liquid amine. If the direct combination of the reactants produces a high

temperature gradient, the amine may be diluted with a solvent such as methanol and added gradually with constant stirring to the halotheophylline. The solvent and the excess amine are then removed at reduced temperatures and pressures, leaving the halo-theophylline-amino salt as a dry solid.

Another method of preparation may be used, particularly where the amine is insoluble in water. In this case the amine is converted to the more water soluble amine hydrochloride by treatment with hydrochloric acid and then dissolved in water. The halotheophylline, in the form of its sodium salt, is then introduced in the proper molar proportions with vigorous stirring to obtain complete solution. The solution is then concentrated at reduced temperatures and pressures until crystallization begins. Next the solution is cooled and the halotheophylline-amine salt is removed by filtration and dried in a vacuum dessicator.

The following specific examples will illustrate several specific reaction procedures in preparing the compounds of the present invention:

Example 1.—8-chlorotheophylline methylamine

Fifty cc. of a 40% methylamine solution were diluted with an equal volume of water. To this solution small portions of 8-chlorotheophylline were added until a total of 21.5 grams (0.1 M) were added. The contents were thoroughly mixed after each addition of the solid chlorotheophylline, and complete solution resulted. This solution was filtered and the filtrate concentrated at reduced temperatures and pressures until crystallization began to occur. After cooling of the mixture, the crystals were removed and filtered in a vacuum filter. The product was dried overnight in a vacuum desiccator which contained calcium chloride. Analysis for chlorotheophylline indicated the composition of this salt to contain one mole of chlorotheophylline for every mole of methylamine. The structure of the resulting salt is as follows:

Example 2.—8-bromotheophylline ethylenediamine

120 cc. of ethylenediamine (95-100%) were dissolved in 250 cc. of absolute methanol and added gradually with thorough mixing and occasional cooling to 259 g. (1.0 M) of 8-bromotheophylline. A thick slurry resulted, and this slurry was heated on a water bath maintained at a temperature of 60° C. and at reduced pressure to remove alcohol and the excess amine. The resulting hard cake was broken up and ground to a fine powder. Analysis of this material showed a molar ratio of 1 to 1 for the halotheophylline and amine indicating that a true molecular compound had been formed. This fact was also substantiated by the fact that the salt had a relatively sharp melting point. The resulting salt has the following structure:

It is also within the scope of the present invention to react the 8-halo-theophylline and the amine in proportions other than the 1 to 1 molar proportions employed in the above examples. Where, for example, a diamine such as ethylenediamine is used, 2 moles of the halotheophylline to 1 mole of the diamine may be employed to produce a double salt of the halo-theophylline and diamine compound.

It will also be appreciated that in the reaction given above the chlorotheophylline can be substituted for the bromotheophylline, and vice versa, with due regard to the difference in molecular weights between these compounds. Similarly, other amine compounds having solubility characteristics similar to the methylamine and the ethylenediamine of the examples can be reacted in the same manner.

In testing the compositions of the present invention for their diuretic action, the following procedure was used:

20 When rats are given tap water perorally on the basis of 5 cc. of water per 100 g. of body weight of each rat, on the average of 100% of the water so given will be excreted as urine over a four-hour period. If, in addition to the water, the rats are each given sub-
25 cutaneously $\frac{1}{2}$ unit of pitressin, an anti-diuretic drug, only 42% of the water, on the average, will be excreted. In conducting this test, the drug to be tested is given in a dosage on the basis of 0.1 g. of the product per kilogram body weight of the rat and the product is
30 added in this proportion to the water and pitressin. In this way, the anti-pitressin action of each of the various compounds is tested in terms of the percent of water recovery from the rats.

Table I illustrates some of the physical properties of the compounds of the present invention, as well as their diuretic activities determined in accordance with the foregoing procedure.

It should be noted that in some instances the halo-theophylline derivative of the amine is apparently the only type of theophylline derivative which will react to form salts with that amine. For example, it was found that the cyclohexylamine and n-butylamine would not react with normal theophylline whereas the halo derivatives of the theophylline would readily react with the respective amines and form true salts.

45 The diuretic activity of the halotheophylline compounds was also compared in a series of tests with the diuretic activity of the straight theophylline compounds of the same amines. In the case of benzylamine, the straight theophylline derivative had a diuretic activity of 73. When the theophylline was substituted by bromotheophylline, and the corresponding bromotheophylline-benzylamine salt prepared, the resulting compound had a diuretic activity of 102. Similarly, the theophylline salt of 2-amino-2-methyl-1-propanol has a diuretic activity of 66 whereas the bromotheophylline 2-amino-2-methyl-1-propanol had a diuretic activity of 116. Under the same test conditions, theophylline-ethylenediamine has a diuretic activity of 75 whereas the bromotheophylline derivative of ethylenediamine has a diuretic activity of 118.

113. The diuretic activity of a compound, as measured by the above test, is a good indication of its effectiveness in the relief of pre-menstrual tension among human females. The relief of pre-menstrual tension by the diuretic compounds of the present invention may be explained when it is appreciated that pre-menstrual tension is a symptom-complex related to abnormal water storage during the pre-menstrual period and is essentially a water 65 toxemia. The intensity of these symptoms vary directly as the amount of water retained, and relief of the symptoms 70 accompanies the diuresis.

It will be understood that modifications and variations may be effected without departing from the scope of the 75 novel concepts of the present invention.

Compound	Percent Halotheo- phylline Calculated	Percent Halotheo- phylline Found	Melting Point	Approximate Solubility, g./100 cc.	Diuretic Activity
Chlorotheophylline-methylamine.	87.4	86.4	above 300	33	99

Bromotheophylline - p - methoxy-benzylamine.	65.3	64.0	109-112	1.5	95

We claim as our invention:

1. A salt having the following formula:

wherein Hal is selected from the group consisting of chlorine and bromine and R is a group selected from the group consisting of saturated aliphatic and cycloaliphatic hydrocarbon groups having not more than 6 carbon atoms, and Z is a radical selected from the group consisting of H , OH , and NH_2 .

2. A therapeutic product as defined in claim 1, in which the primary amine is an alkyl monoamine.

which the primary amine is an alkyl monoamine. 3. A therapeutic product as defined in claim 1, in which the primary amine is an alkylene diamine.

4. A therapeutic product as defined in claim 1, in which the primary amine is a polyalkylene polyamine.

5. A therapeutic product as defined in claim 1, in which the primary amine is ethylene diamine.
